ENGINE STARTER

Edward N. Jacobi, Milwaukee, Wis., assignor to
 Briggs & Stratton Corporation, Milwaukee,
 Wis., a corporation of Delaware

Application October 23, 1944, Serial No. 559,898

9 Claims.

(Cl. 74—7)

This invention relates to engine starters of the so-called automatic type wherein the pinion is automatically propelled into and out of mesh with the ring gear of an engine to be started. Such a starter has been shown and described in the co-pending application of Mary C. Fitzgerald, executrix of the estate of John W. Fitzgerald deceased, for Engine starter, filed June 19, 1943, Serial No. 491,513, now Patent No. 2,368,292.

As in all of the automatic type starters, the pinion is propelled into and out of mesh with the engine ring gear as a result of relative rotation between cooperating threaded parts one of which is drivingly connected with the pinion while the other rotates with the power shaft of the starter.

The present invention differs from the engine starter of the aforesaid co-pending application, however, in the specific manner in which end thrust of the pinion is absorbed and cushioned, and also in the manner in which the driving connection is established between the pinion and its screw threaded actuator.

One of the objects of this invention, therefore, resides in the provision of an engine starter of the character described wherein the translating and torque transmitting connection between the pinion and its actuator includes a nut member threaded on the actuator and splined to the pinion.

Another object of this invention is to provide an engine starter of the character described with novel means reacting between the pinion and nut member for cushioning and absorbing end thrust of the pinion.

A further object of this invention resides in the provision of cup shaped spring washers so designed and arranged as to directly receive and cushion thrust of the pinion with properly proportioned responses both upon improper meshing of the pinion teeth with those of the engine ring gear and during initial cranking of the engine at which time the starter receives the full load of the engine.

Still another object of this invention is to provide a simplified engine starter assembly capable of being installed as a unit on the power shaft of the starting motor.

With the above and other objects in view, which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawing illustrates one complete example of the physical embodiment

of the invention constructed in accordance with the best mode so far devised for the practical application of the principles thereof, and in which:

5 Figure 1 is a longitudinal cross sectional view through the starter of this invention showing the pinion in retracted position;

10 Figure 2 is a view similar to Figure 1 but partly in elevation and partly in cross section and illustrating the positions of the parts during cranking of the engine; and

15 Figure 3 is a cross sectional view taken through Figure 1 on the plane of the line 3—3.

Referring now more particularly to the accompanying drawing in which like numerals indicate like parts, the numeral 5 designates the power shaft of a starting motor 6 upon which the starter assembly indicated generally by the numeral 7 is mounted.

20 The starter unit comprises a tube 8 slipped over the inner end of the power shaft and upon which the customary pinion 9 is freely rotatable and slidable between stops 10 and 11 on the tube to define its operative position of mesh with the ring gear 12 and its retracted position respectively. The stop 11 in this case is actually the forward end of a pinion actuator 13 which has a hub portion 14 bored to slip over the outer end of the power shaft.

25 30 The forward portion 15 of the actuator has a counterbore 16 to receive the outer end of the tube 8 and these parts are rigidly joined together at the counterbore as by brazing, indicated generally by the numeral 17.

35 Preferably the engaging portions of the tube and actuator are partially threaded as shown at 18 so that the brazing material placed at the bottom unthreaded portion of the counterbore flows into the threaded connection to form a more perfect union between the tube and actuator.

40 45 The forward portion 15 of the actuator has screw threads 19 cut into its exterior and it is to be noted that the outer diameter of the hub portion 14 of the actuator is less than the root diameter of the screw threads. Such proportion of the actuator facilitates machining of its threads by affording clearance for the threading tool during the threading operation.

50 55 The connected tube and actuator are anchored to the power shaft 5 for rotation therewith by means of a metal ring 20 brazed or otherwise secured to the hub of the actuator to reinforce the same and a set screw 21, passing through a threaded hole in the reinforced hub and entering the shaft as shown.

Threaded onto the exterior of the actuator is a nut member 22 adapted to control the motion of the pinion toward and from mesh with the ring gear 12 upon relative rotation between the nut

member and actuator, and to impart driving torque to the pinion upon interference with forward motion thereof toward the ring gear.

For this purpose, the nut member has an extension 23 projecting forwardly therefrom toward the rear of the pinion and serrated to form teeth 24 equal in number to those of the pinion and meshing therewith so as to provide a splined driving connection between the nut member and the pinion.

To keep the diameter of the parts at a minimum it will be noted that the teeth of the pinion are cut down at the rear thereof so as to provide stub teeth 25 and to insure a shallow splined connection with the nut member extension. Thus, it will be noted that the pinion has a positive torque transmitting connection with the nut member, and that these parts are relatively axially movable toward and from each other.

A sleeve 26 of approximately the same diameter as that of the pinion is rigidly secured thereto and extends rearwardly therefrom toward the nut member to encircle the splined connection between the nut member and pinion. Four circumferentially arranged tangs 27 project from the forward edge 28 of the sleeve and are received in the spaces between adjacent pinion teeth. These tangs have lateral ears 29 projecting into peripheral slots 30 cut into the tops of the regular pinion teeth to thereby cooperate with the tangs and the forward edge 28 of the sleeve which abuts the rear of the full height pinion teeth as shown to securely anchor the sleeve.

In practice the ends of the tangs 27 are bifurcated and the bifurcated ends staked into the slots 30 to form the lateral ears 29.

Relative axial motion of the pinion and nut member in a direction away from each other is limited by means of a series of prongs 31 sprung inwardly from the wall of the sleeve to engage abutments 32 formed at the forward extremities of the serrations 24 of the nut member. The abutments 32 and prongs 31 also cooperate with the stop 11 to define the limit of rearward motion of the nut member relative to the actuator.

As stated previously, it is the function of the nut member 22 to effect forward propulsion of the pinion toward mesh with the engine ring gear upon relative rotation in one direction between it and the actuator. Such motion is imparted to the pinion by means of spring means 33 confined between an annular abutment 34 on the rearward end of the nut member and the rear edge of the sleeve 26 so as to yieldingly resist relative motion of the pinion and nut member toward each other. The spring 33 has as its function the cushioning of end thrust of the pinion developed both upon improper meshing of the gears and as the starter picks up the load of the engine.

The spring means herein shown is comprised of a plurality of pairs of cupped opposed spring washers, there being one pair of opposed spring washers 35 of relatively light weight metal and two pairs of opposed spring washers 36 made of heavier metal. These washers are received on the exterior of the nut member with the outer peripheries of each pair of washers engaging each other and with the inner peripheries of washers of adjacent pairs likewise contacting one another to form a stack having resiliencies of different value. Thus, the light washers 35 are adapted to yield in response to the relatively light thrust of the pinion developed by improper meshing of the gears while all of the washers yield to the rela-

tively heavy thrust of the pinion developed as cranking is initiated.

During initial operation of the starter the connected pinion and nut member by inertia do not rotate despite rotation of the power shaft and the pinion actuator 13. Since the nut member 22 is drivingly splined to the pinion it follows that relative rotation between the actuator and nut member causes the nut member to move forwardly along the threads of the actuator and to exert a yielding force on the pinion through the spring washers 35 and 36 sufficient to cause the pinion to be propelled into mesh with the engine ring gear.

Upon interference with propulsion of the pinion to its meshing position with the ring gear such as during improper meshing of the gear teeth, the nut member continues to move axially forward and the end thrust of the pinion is absorbed by the spring washers 35 thus reducing the noise of improper meshing to a minimum.

Such interference and cushioning of end thrust during improper meshing of the gears, however, initiates torque transmission from the actuator 25 to the pinion and the pinion is caused to rotate sufficiently to bring its teeth into register with those of the engine ring gear at which time the expansive force of the washers 35 quickly meshes the pinion with the ring gear.

The full meshing position of the pinion with the ring gear is defined by engagement of the forward end of the pinion with the stop 10 secured to the inner end of the tube 8 and upon such interference with its forward motion the nut member continues to move forwardly toward the pinion against the combined action of the spring washers 35 and 36. Hence, application of the engine load onto the starter is gradual and the thrust of the pinion effectively cushioned.

Obviously when further compression of the spring washers 35 and 36 is impossible as shown in Figure 2, the pinion is caused to rotate with the power shaft 5 and cranking of the engine results. After the engine starts the pinion is expelled from mesh in the customary manner by the overrunning condition at the threaded connection between the pinion nut member and the actuator.

Consequently, it will be seen that the nut member is screwed outwardly back onto the pinion actuator in a more or less free manner until engagement between the abutments 32 on the nut member with the prongs 31 causes the pinion to be drawn along with the nut member out of mesh with the ring gear.

Attention is directed to the fact that propulsion of the pinion to its meshing position is made more positive by reason of the increased mass and inertia of the pinion resulting from the weight of the spring washers being added to that of the pinion and nut member.

From the foregoing description taken in connection with the accompanying drawing, it will be readily apparent that this invention provides a unitary starter of unique construction wherein the parts of the starter are not only held to a desirable minimum but are designed with maximum simplicity.

70 What I claim as my invention is:

1. An engine starter of the character described comprising: a pinion movable axially along a power shaft between retracted and operative positions with respect to the ring gear of an engine to be started; a screw threaded driver;

a nut member having threads engaged with those of the driver whereby relative rotation therebetween effects axial movement of the nut member relative to the driver; means including the teeth of the pinion providing a splined driving connection between the nut member and pinion; a shell fixed to the pinion teeth and having an outer diameter substantially no greater than that of the pinion and extended from the pinion teeth toward the nut member so as to overlie part of the nut member; interengageable means on the shell and nut member for limiting relative axial motion between the pinion and nut member; and a plurality of cupped spring washers confined in a stack between the nut member and an abutment on the shell so as to yieldingly resist relative motion of the pinion and nut member toward each other and through which the pinion is propelled toward its operative position of mesh with the engine ring gear in consequence to relative rotation in one direction between the actuator and nut member, said spring washers being arranged to cushion end thrust of the pinion developed upon interference with axial motion thereof toward the engine ring gear, certain of said spring washers being of relatively light material so as to yield in advance of the remaining washers in response to the relatively light thrust of the pinion developed upon improper meshing thereof with the engine ring gear, but all of said spring washers being adapted to yield in response to the relatively heavy thrust of the pinion developed as the starter picks up the load of the engine.

2. An engine starter of the character described, comprising: a pinion movable axially along a power shaft toward and from mesh with the ring gear of an engine to be started; a screw threaded actuator drivingly connected with the power shaft to rotate therewith; stop means on the actuator engaged by the pinion to define its retracted position; a nut member having threads engaged with those of the actuator whereby relative rotation therebetween effects axial movement of the nut member relative to the actuator; means on the nut member cooperating with the teeth of the pinion to provide a splined driving connection between the nut member and the pinion permitting relative axial movement therebetween; a shell fixed to the pinion and extending therefrom to substantially cover said splined connection; cooperating parts on the shell and the nut member for limiting relative axial motion of the pinion and the nut member away from each other and to maintain the splined connection therebetween; and spring means confined between the nut member and an abutment on the shell so as to yieldingly resist relative axial movement of the pinion and nut member toward each other and through which the pinion is propelled toward its position of mesh with the engine ring gear in consequence to relative rotation in one direction between the actuator and nut member, said spring means being operable to cushion the thrust of the pinion developed upon interference with axial motion thereof toward the engine ring gear.

3. An engine starter of the character described, comprising: a pinion movable axially along a power shaft toward and from mesh with the ring gear of an engine to be started; stub teeth at the end portion of the pinion remote from the ring gear aligning with the teeth at the forward end of the pinion; a screw threaded actuator drivingly connected with the power shaft so as

to rotate therewith; a nut member having threads engaged with those of the actuator whereby relative rotation therebetween effects axial movement of the nut member relative to the actuator; teeth formed at one end of the nut member and meshing with the stub teeth of the pinion to form a splined driving connection between the nut member and pinion permitting relative longitudinal motion between the pinion and nut member; a shell fixed to the pinion and extending from said end portion thereof to encircle the splined connection between the nut member and pinion; cooperating abutments on the shell and the nut member for limiting relative axial motion of the pinion and nut member away from one another so as to prevent separation of the splined driving connection therebetween; and spring means confined between the nut member and an abutment on the shell so as to yieldingly resist relative axial movement of the pinion and nut member toward one another and through which the pinion is propelled toward mesh with the engine ring gear in consequence to relative rotation in one direction between the actuator and nut member, said spring means being operable to cushion the thrust of the pinion developed upon interference with its forward motion toward mesh with the engine ring gear.

4. In an engine starter having a power shaft: 30 a tube telescoped over the inner end of the shaft; a pinion actuator having a hub telescoped over the outer end of the shaft and an externally threaded inner portion provided with a counterbore to receive a portion of the tube; means fixedly joining the actuator and tube at said counterbore; means for securing the connected tube and actuator to the power shaft for rotation therewith; a pinion axially slidable and rotatable on the tube inwardly of the actuator; a nut member having threads engaged with those of the actuator whereby relative rotation therebetween effects axial movement of the nut member relative to the actuator; a splined driving connection between the nut member and the pinion permitting relative axial motion of the pinion and nut member toward and from one another; means limiting relative axial motion of the pinion and nut member in a direction away from one another to thereby prevent separation of said splined driving connection; and spring means confined between the nut member and a part on the pinion so as to resist relative motion of the pinion and nut member toward each other and through which the pinion is propelled inwardly toward its position of mesh with the engine ring gear in consequence to relative rotation in one direction between the actuator and nut member.

5. In an engine starter having a power shaft: a tube telescoped over the inner end of the shaft; an actuator having a hub telescoped over the outer end of the shaft and an externally screw threaded inner portion provided with a counterbore to receive a portion of the tube adjacent thereto, the hub of the actuator being smaller in diameter than the root diameter of the screw threads of the actuator; means inside said counterbore fixedly joining the tube and the actuator; means for securing the connected actuator and tube to the power shaft for rotation therewith including a separate reinforcing ring encircling the hub of the actuator and fixed thereto, and a set screw passing through said ring and the hub of the actuator and entering the shaft; a pinion slidably and rotatable on the tube inwardly of the actuator; a nut member having threads en-

gaged with those of the actuator whereby relative rotation therebetween effects axial movement of the nut member relative to the actuator; a splined driving connection between the nut member and pinion permitting relative axial motion of the pinion and nut member toward and from each other; means for limiting relative axial motion of the pinion and nut member in a direction away from one another to thereby prevent separation of said splined driving connection; compression spring means interposed between the nut member and a part on the pinion so as to yieldingly resist relative axial motion of the pinion and nut member toward each other and through which the pinion is propelled toward its position of mesh with the engine ring gear in consequence to relative rotation in one direction between the actuator and nut member; and a pinion stop mounted on the inner extremity of the tube and against which the pinion abuts to define the meshing position of the gears.

6. An engine starter of the character described, comprising: a pinion movable axially along a power shaft toward and from mesh with the ring gear of an engine to be started; a screw threaded actuator drivingly connected with the power shaft so as to rotate therewith; stop means on the actuator engageable by the pinion to determine the retracted position of the pinion; a nut member having threads engaging with those of the actuator whereby relative rotation therebetween effects axial movement of the nut member relative to the actuator; a splined driving connection between the nut member and the pinion permitting relative longitudinal motion therebetween; a shell fixed to the pinion and extended therefrom toward the nut member; cooperating abutments on the shell and the nut member for limiting relative axial movement of the nut member and pinion away from one another and acting jointly with said actuator stop means to define the normal inoperative position of the nut member; and spring means confined between cooperating shoulders on the nut member and shell to resist relative longitudinal motion of the pinion and nut member toward each other and through which the pinion is propelled toward its position of mesh with the engine ring gear upon relative rotation in one direction between the actuator and the nut member.

7. An engine starter of the character described, comprising: a pinion movable axially along a power shaft toward and from mesh with the ring gear of an engine to be started; stub teeth at the end portion of the pinion remote from the ring gear substantially forming continuations of the teeth at the forward end of the pinion; a screw threaded actuator fixed on the power shaft to rotate therewith, the end of the actuator adjacent to the pinion serving as a stop to limit motion of the pinion away from the ring gear; a nut member threaded on the actuator; teeth integral with the nut member and extending therefrom in meshing relationship with the stub teeth of the pinion to provide a splined driving connection between the nut member and pinion permitting relative axial motion therebetween; and spring means confined between abutments on the nut member and pinion to resist relative axial motion of said parts toward each other and whereby relative rotation in one direction between the nut member and actuator effects translation of the pinion into mesh with the engine

ring gear, said spring means comprising at least one light and one heavy spring element to absorb light and heavy thrusts of the pinion respectively.

5 8. An engine starter of the character described, comprising: a pinion movable axially along a power shaft between retracted and operative positions with respect to the ring gear of an engine to be started; a screw threaded driver; a nut member threaded on the driver whereby relative rotation therebetween effects axial movement of the nut member relative to the driver; means including the teeth of the pinion providing a splined driving connection between the nut member and the pinion; a shell fixed to the pinion teeth and having an outer diameter substantially no greater than that of the pinion and extended from the pinion teeth toward the nut member so as to overlie part of the nut member; interengageable means on the shell and nut member for limiting relative axial motion of the pinion and nut member away from each other; and spring means confined between the nut member and an abutment on the shell so as to yieldingly resist relative motion of the pinion and nut member toward each other and through which the pinion is propelled toward its operative position of mesh with the engine ring gear in consequence to relative rotation in one direction between the actuator and nut member.

30 9. In an engine starter of the character described having a rotatable power shaft: a screw threaded actuator fixed on the power shaft to rotate therewith; a pinion movable axially along the power shaft toward and from mesh with the ring gear of an engine to be started; means on the actuator engaged by the pinion upon axial motion thereof away from the engine ring gear to determine the retracted position of the pinion; a driving connection between the actuator and the pinion operative to propel the pinion axially into mesh with the engine ring gear upon initial rotation of the actuator and to thereafter transmit cranking torque to the pinion including a nut member threaded on the actuator, stub teeth at the end of the pinion adjacent to the actuator, an extension on the nut member having relatively shallow teeth formed thereon and meshed with the stub teeth of the pinion so as to provide a splined driving connection between the nut member and pinion permitting relative axial motion therebetween, a shell fixed to the pinion teeth and extending rearwardly therefrom toward the actuator to encircle said splined connection and consequently the extension on the nut member, said shell having a diameter substantially no greater than that of the pinion teeth, and spring means interposed between abutments on the nut member and shell so as to yieldingly resist relative axial motion of the pinion and nut member toward each other and through which the pinion is advanced toward mesh with the engine ring gear upon relative rotation in one direction between the actuator and nut member; cooperating abutments on the nut member teeth and the shell for limiting relative axial motion of the pinion and nut member apart so as to maintain said splined connection operative; and a stop on the shaft against which the pinion abuts to define the operative meshing position thereof with the engine ring gear.
